AMMUNITION FOR LINE THROWING GUNS AND THE LINE CARRYING RING THEREFOR

Filed Oct. 16, 1923

FIG. 1.

FIG. 4.

FIG. 3.

FIG. 2.

Inventor
John W. Stockett

By W. N. Roach
Atty.

UNITED STATES PATENT OFFICE.

JOHN W. STOCKETT, OF WASHINGTON, DISTRICT OF COLUMBIA.

AMMUNITION FOR LINE-THROWING GUNS AND THE LINE-CARRYING RING THEREFOR.

Application filed October 16, 1923. Serial No. 668,875.

(FILED UNDER THE ACT OF MARCH 3, 1883, 22 STAT. L., 625.)

To all whom it may concern:

Be it known that I, JOHN W. STOCKETT, a citizen of the United States, and a resident of Washington, District of Columbia, have invented an Improvement in Ammunition for Line-Throwing Guns and the Line-Carrying Ring Therefor, of which the following is a specification.

The invention described herein may be used by the Government, or any of its officers or employees in prosecution of work for the Government, or by any other person in the United States, without payment to me of any royalty thereon, in accordance with the act of March 3, 1883.

This invention relates to the ammunition for line throwing guns and the line carrying ring therefor.

In line throwing guns it is desirable that the propellant charge and its container be entirely expelled from the gun when fired or entirely consumed by the gases from the propelling charge, so that no unconsumed particles will be left when the next charge is inserted.

The main object of the invention is, therefore, to provide a round of fixed ammunition having a propellant charge and container fixedly connected therewith in such a manner that the projectile and its propelling charge may be loaded into the gun at its muzzle end as a single unit, and such that after discharge of the gun, no portion of the powder container will be left in the bore of the gun, to interfere with the loading of the next round into the gun.

A further object of the invention is to provide a projectile formed in rear of its center of gravity with means against which a line carrying member is adapted to seat as the projectile passes from the muzzle of the gun.

With these and other objects in view, my invention resides in the novel arrangement and combination of parts and in the details of construction hereinafter described and claimed, it being understood that changes in the precise embodiment of the invention herein disclosed may be made within the scope of what is claimed without departing from the spirit of the invention.

Practical embodiments of the invention are shown in the accompanying drawing, wherein

Fig. 1 is a fragmentary view in side elevation, partly in section, of a round constructed in accordance with the invention; 55

Fig. 2 is a similar view of a modified form of the device; and

Fig. 3 is a view in elevation of the line 60 carrying ring; and

Fig. 4 is a section through the ring.

Referring to the drawings by numerals of reference:

A round constructed in accordance with 65 my invention consists of a projectile 1 formed preferably with an annular shoulder 2 located rearwardly of the center of gravity of the projectile and with a reduced base portion 3.

Secured to the base portion 3, in any suitable manner, as by frictional contact therewith, is a container 4 in which is carried the propelling charge. This container 4 may be of any desired type. In one embodiment 75 of my invention the container is provided with a series of perforations 5 through which the gases formed by the ignition of the propellant charge may escape.

The propellant charge, not shown, is 80 packed within the container. To prevent particles or grains of the propellant charge from escaping through the perforations 5 the container may be encircled by a gauze fabric 6. The fabric is preferably held in place by shellac or other suitable waterproof adhesive, in order to keep moisture from the powder charge, which would otherwise be ruined if allowed to get wet.

When the igniting primer is fired the flash 90 passes through the perforations igniting the propellant charge. The gases of the propellant charge, escaping through the perforations, serve not only to propel the projectile from the gun barrel but also the container 4, which is thus expelled from the gun. 95

In the modification shown in Fig. 2 the projectile is the same as that heretofore described but the container in this instance is 100 formed with walls 4' of inflammable material, such as nitrocellulose, which is ig-

nited by the flash of the primer igniting the propellant charge and is entirely consumed therewith.

As the projectile passes from the gun the shoulder 2 is brought into contact with a line carrying ring 7 shown in Figs. 3 and 4, which is suitably mounted upon the gun, adjacent the muzzle thereof, preferably, in a counterbore in the muzzle as described in my copending application Serial No. 668,874 filed Oct. 16, 1923, now Patent No. 1,483,129, issued Feb. 12, 1924, and is provided with two openings or eyes 8, for the attachment of the projectile line. As stated heretofore the shoulder 2 is preferably located rearwardly of the center of gravity of the projectile. This arrangement is preferred in order that the projectile as it carries the ring on its trajectory may be properly balanced so that tumbling of the projectile will be prevented and the breaking of lines, a common occurrence with projectiles heretofore used may be avoided. The line ring 7, may, if desired, be provided with a reduced portion 9, for supporting it in a suitable counterbore in the barrel of the gun at the muzzle end. In order to provide ample strength and to prevent splitting the ring 7 when the engaging shoulder 2, on the projectile comes into engagement with the ring where a ring seated in the counterbore is employed, I provide

that portion 10 of the line carrying ring, which is exterior or forward of the counterbore in the gun with a greater cross-sectional area than the remainder of the ring.

I claim:

1. A round of fixed ammunition, including a projectile formed with an annular shoulder toward its base, a perforated container secured to the base and a gauze fabric covering the container.
2. A round of fixed ammunition, including a projectile formed with an annular shoulder toward its base and a perforated container connected to the projectile in such manner as to be expelled therewith from a gun on firing the same, said container being adapted to fit over the base of the projectile in the rear of the shoulder.
3. A round of muzzle loading fixed ammunition, including a projectile formed with an annular enlargement near its base, and a water proof inflammable propellant container fitted over the rear end of the projectile and resting against the enlargement.
4. A round of muzzle loading fixed ammunition, including a projectile formed with an annular enlargement near its base which serves as a line ring carrying member and a water proof combustible propellant container connected to the base of the projectile and resting against said enlargement.

JOHN W. STOCKETT.
